METHOD FOR REFINING OXY-ACIDS OBTAINED FROM OXIDIZED HYDROCARBONS

Arthur L. Blount, Palos Verdes Estates, Calif., assignor to Union Oil Company of California, Los Angeles, Calif., a corporation of California

No Drawing. Application January 4, 1937,
Serial No. 118,999

6 Claims. (Cl. 260—452)

The present invention relates to the oxidation of hydrocarbons, and more particularly pertains to the production of new and useful products resulting from liquid phase oxidation of petroleum hydrocarbons. More specifically stated, the invention covers a treatment of products resulting from the liquid phase oxidation of petroleum hydrocarbons with oxygen or an oxygen-containing gas, said treatment causing the separation or 10 isolation of certain oxygenated products having distinct and valuable characteristics and utilities:

It is well known that the liquid phase oxidation of hydrocarbons gives rise to a wide variety of products embracing unsubstituted carboxylic acids, hydroxy acids, keto acids, aldehyde acids, 15 alcohols, esters, ethers, ketones, lactones, resinous and resin-forming materials and a number of other more or less oxygenated products. Also, unless the liquid phase oxidation is carried out 20 for excessively long periods of time and under excessive operating conditions, a certain quantity of hydrocarbons is usually left in an unreacted or uncombined condition. It is also known that the liquid phase oxidation of petroleum fractions, and particularly of those which are obtained from naphthenic or asphalt base crudes 25 results in the formation of a heterogeneous mixture containing most if not all of the above types of more or less oxygenated hydrocarbon products. 30 It is therefore the main object of the present invention to provide a method for treating said products of oxidation to recover or isolate therefrom new and valuable products or fractions having distinct characteristics and utilities. A further object of the invention is to treat the products resulting from the liquid phase oxidation with 35 air of a naphthenic petroleum oil, its fractions and/or distillates, to produce and/or isolate therefrom the aforementioned new and useful 40 products.

As previously stated, the oxidation of a petroleum fraction, particularly of one containing naphthenic constituents, produces a mixture comprising some unreacted or unoxidized hydrocarbons and a number of products which are oxidized to a greater or less extent. These products vary in their solubility in the hydrocarbon fraction and in each other to such an extent that two phases are formed when the oxidation is 45 sufficiently prolonged. In general, the more highly oxidized products such as keto and hydroxy acids, are the least soluble while most of the unsubstituted, some of the substituted carboxylic acids, and certain ethers, esters, lactones, etc., are found to be relatively more soluble in 50

each other and in the unreacted hydrocarbons. It is therefore obvious that the heterogeneous mass produced by the liquid phase oxidation of petroleum and particularly naphthenic hydrocarbons may be easily separated into two fractions by allowing the mass to stand. One of the phases thus produced, as mentioned above, contains the unconverted or uncombined hydrocarbons and the products of oxidation soluble therein, while the insoluble phase which deposits out upon standing contains most of the highly oxidized products as well as certain oxygenated substances now believed to comprise polyhydric alcohols. These phases may be easily separated from each other as by a simple decantation. For 5 purposes of simplicity, the first mentioned fraction or phase will be hereinafter referred to as the "oil-soluble" phase or fraction, and the acids therein will be termed as the "oil-soluble" acids. On the other hand, the fraction generally insoluble in the oil-soluble phase will be hereinafter 10 termed as the "oil-insoluble" fraction or phase. The present invention primarily deals with the oil-soluble fraction and the oil-soluble acids contained therein. Therefore, it is a still further object of the present invention to treat the oil-soluble fraction obtained during the above 15 described liquid phase oxidation to isolate therefrom certain types of new and useful acids having certain distinctive characteristics and utilities which will be described more fully hereinbelow. 20

It has recently been discovered that the oil-soluble phase obtained by the liquid phase oxidation of a predominantly naphthenic petroleum fraction may be fractionated to isolate therefrom certain of its constituent fractions, said separation or isolation being realized by a series of steps which will be described and pointed out hereinbelow in connection with the typical description 25 of a preferred form of realization. Thus, the free carboxylic acids and easily saponifiable lactones, etc. contained in the oil-soluble phase may be removed therefrom by treating said oil-soluble phase with an alkali to convert the aforementioned substances into their soaps or salts, while leaving the unconverted petroleum hydrocarbons, as well as certain of the oxygenated products, such as ethers and alcohols, in an unchanged 30 form. The aqueous soap solution produced by this saponification may then be separated from the unreacted fraction as by decantation, the acids thus saponified being then liberated as by the addition of inorganic acids of the type of 35 sulfuric acid or the like. These oil-soluble acids, 40

obtained as the result of the first steps of separation, are fluid and of dark color. Chemically, they are roughly classed as consisting predominantly of unsubstituted and substituted carboxylic acids such as naphthenic acids, hydroxy acids, keto acids, and certain resin-forming acids. This classification is based on the observed acid numbers, saponification values and oxygen contents. It is, however, obvious that this evidence 10 is far from conclusive as to the exact character of such a complex mixture. It has been found, however, that these oil-soluble acids contain fractions which vary greatly in their chemical and physical properties and that for some uses the 15 action of one fraction is antagonistic to that of another, so that the full utility of the product is available only upon the resolution of said oil-soluble acids into simpler and more coherent fractions.

20 The oil-soluble acids may be segregated or separated into two fractions by extraction with a petroleum ether or a similar light hydrocarbon diluent or solvent. This extraction causes phase separation in that certain of the acids and particularly the relatively more highly substituted acids are found to be insoluble in said diluent or solvent. In what will follow hereinbelow these insoluble acids will be referred to as the "petroleum ether-insoluble acids." Generally 25 speaking, these crude petroleum ether-insoluble acids are insoluble in propane, but completely miscible with kerosene, benzene, alcohol, acetone and carbon tetrachloride.

It has now been discovered that these petroleum ether-insoluble acids may be effectively resolved into still further constituent fractions when said organic acids are treated with oxygen-containing di- or tri-basic inorganic acids, such as sulfuric acid or phosphoric acid. It has been 30 further discovered that these oxygen-containing inorganic acids are effective solvents or reagents in said resolution of the crude petroleum ether-insoluble acids when said inorganic acids are used in conjunction with organic diluents or solvents in a manner more fully described hereinbelow. It is therefore a still further object of the present invention to provide a process whereby the relatively complex petroleum ether-insoluble acids, obtained as one of the fractions 35 derived from the treatment of products of liquid phase oxidation of petroleum hydrocarbons, may be treated with oxygen-containing di- or tri-basic inorganic acids to produce or isolate from said petroleum ether-insoluble acids simpler 40 fractions of a more homogeneous character and consequently of greater utility.

For the purpose of exposition the invention will be more fully described in conjunction with a typical example, the various phases of the invention being discussed at greater length in connection therewith.

Approximately 38,000 grams of an untreated topped light gas oil fraction obtained from naphthenic or asphalt base crude oil, having a 45 boiling point range of 393-612° F., a gravity of about 33° A. P. I. and containing approximately 79% of naphthenes and paraffins, about 19% of aromatics and about 2% of unsaturates, was oxidized by agitating with air for a period of 50 about seven hours at a pressure of approximately 100 lb. gauge and at an average temperature of 300° F. This oxidation was realized in the presence of a catalyst consisting of approximately 210 grams of magnesium oxide. By separation 55 of the soluble and insoluble phases, an oil soluble

phase was obtained which weighed 28,425 grams and comprised 74.73% of the original charging stock. The acid number of this oil-soluble phase was 21 mg. KOH/g., while the saponification value was equal to 47. Since some of the acids contained in said oil-soluble phase were known to be water-soluble, the whole oil-soluble phase was washed with water. The water-soluble acids extracted by this washing weighed about 175 grams, had an acid number of 378 and a saponification 60 value of 427. These acids were slightly soluble in benzene, alcohol and acetone, were somewhat soluble in kerosene but insoluble in propane, petroleum ether, and carbon tetrachloride. In order to remove the unreacted gas oil, as well as certain of the ethers, esters, etc., the washed oil-soluble phase was commingled in a cold state with an aqueous solution of sodium hydroxide. This treatment caused the saponification of all 65 of the unsubstituted and substituted acids having a free carboxylic group. The saponified materials, being soluble in water, were found in the aqueous phase, so that a substantial separation of the unoxidized gas oil and of the unsaponified oxygenated products was realized by a mere decantation and separation of the phases thus produced. The oil-soluble acids saponified by the above described treatment with cold sodium hydroxide were then liberated by the addition 70 to the soap solution of requisite quantities of an inorganic acid, such as sulfuric acid. As in the previous treatment, the acidification again caused the formation of two phases, the oily phase consisting of the gas oil-soluble acids, and the aqueous phase consisting of the salt water. After separating the salt water, the oil-soluble acids were found to weigh 1,838 grams or 4.8% 75 on the basis of the original charge. The acid number of this mixture of acids was 164 mg. KOH/g., while the saponification number was 40. 80 In order to further simplify the composition of the acids present in the oil-soluble acid phase, this mixture of acids was treated or extracted with petroleum ether or a like solvent, such as low boiling naphtha, gasoline, etc. Although the optimum quantity of petroleum ether used for this extraction depends on the type and character of the original material oxidized, and therefore of the mixture of acids comprising the oil-soluble acid phase, it has been found that 85 quantities ranging from equal volumes of petroleum ether and of the oil-soluble acids to 10 volumes of the former to 1 volume of the latter, produces the best results. The optimum results, however, were found to be produced by the dilution of the acids in two volumes of petroleum ether. This extraction causes the precipitation 90 of a mixture of acids which are herein termed petroleum ether-insoluble acids and which have generally the characteristics described more fully hereinabove. In the example described herein the petroleum ether-insoluble acids weighed 519 grams, comprised 1.36% of the original charge, had an acid number of 148 and a saponification 95 value of 208.

In order to treat the petroleum ether-insoluble acids with sulfuric acid in the most advantageous manner it was found necessary first to bring these acids into a more or less dilute solution in a solvent which is relatively inert to the inorganic acid. In most instances preference is given to solvents such as benzene, toluene, or mixtures of naphtha and chloroform. In the present instance the petroleum ether-insoluble acids were dissolved in benzene in the proportion of 1 part 75

of the acids to 9 parts of benzene, the solution being then treated twice with 1 volume percent portions of 70% sulfuric acid at room temperature. The acid sludges being separated, the treated benzene solution was then extracted with dilute caustic to remove the free organic acids therefrom, and the aqueous soap solution thus obtained was decomposed with a mineral acid to yield approximately 340 grams of organic acids hereinafter referred to as the "refined petroleum ether-insoluble acids." The caustic washed benzene solution was then evaporated to yield 65 grams of a material hereinafter referred to as the "petroleum ether-insoluble neutrals." By hydrolyzing the acid sludge, as by strong dilution with water or by the addition of aqueous alkali up to incipient neutralization, a still further oily water-insoluble fraction was obtained with a yield of 70 grams, said fraction being referred to as the "sludge acids." Finally, the two aqueous phases representing the wastes from the caustic extraction and the sludge hydrolysis were extracted with ethyl ether or treated by salting out, evaporation, etc., to yield respectively 35 grams and 10 grams of "water-soluble acids." Thus, according to the process constituting the objects of the present invention, the petroleum ether-insoluble acid phase has been resolved into four fractions, namely, the acid treated petroleum ether-insoluble acids, the petroleum ether-insoluble neutrals, the sludge acids, and the water-insoluble acids. All of these, as will be shown subsequently, are substantially distinct in their chemical and physical properties.

As stated above, the crude petroleum ether-insoluble acids were comparatively dark and had a high viscosity. These acids had an acid number of about 148, a saponification number of 208, and iodine number of 16.2 and an acetyl value of 163. These figures indicate the presence of 0.24 double bond and 1.23 hydroxyl groups per acid equivalent. On the other hand the acid treated or refined petroleum ether-insoluble acids represented a material of a tacky consistency with a dark reddish brown color, the substance being transparent and practically bright red when viewed in thin layers. These acid treated acids had an acid number of 191, a saponification number of 224, an iodine number of 15.4 and an acetyl value of 96. The figures indicate the presence of 0.19 double bond and 0.56 hydroxyl group per acid equivalent. These acid treated petroleum ether-insoluble acids were found to possess the unusual property of forming excellent resins when heated by themselves or with an equivalent quantity of glycerine. This property of resinification is also displayed to some extent by the crude petroleum ether-insoluble acids, but the resins obtained from this latter material have been found to be less satisfactory from the viewpoint of color and consistency.

The sludge acids had an acid number of 147 and a saponification number of 198. They were found to be highly unsaturated and possessed of a high degree of hydroxylation, which makes this acidic fraction of interest for many uses. Additionally these sludge acids were found to display resinifying properties which, however, do not equal those of the aforementioned acid treated petroleum ether-insoluble acids. As to the "neutral" fraction derived as described above, this was a fluid material with a terpene-like odor having an acid number of 33, a saponification value of 125, an acetyl value of 146, and an iodine number of 20. The water-soluble acids had an acid

number of around 250 and a saponification value of 361. This fraction thus represents a mixture of water-soluble hydroxy acids having obvious uses in the various technical and chemical arts.

In the example described above the oil-soluble phase was washed with water prior to extraction with alkali. This step is not necessary and may be omitted, in which case it may be desirable to work up the water from the alkali extraction, after the oil-soluble acids are recovered therefrom by acidification, to recover the water-soluble acids present therein.

That treatment of the petroleum ether-insoluble acids with di- or tri-basic oxygen containing inorganic acids may be realized under various conditions. The optimum concentration of the inorganic acid depends on the character of the material treated and its degree of dilution with an inert solvent. Sulfuric acid has been found effective in concentrations ranging from 40 to 95%, and higher, the most economic concentrations being in the neighborhood of 70-80%. To realize the same degree of treatment with phosphoric acid a slightly higher range of concentration is usually required. The quantity of inorganic acid used can be varied according to the degree of refining desired, but the most practical results are obtained with from 1 to 5 volume percent on the basis of the volume of solution treated. In general, sharper separation and more effective treatment is realized by increasing the degree of dilution of the organic acid with the inert solvent, but the optimum dilution from a practical and economic standpoint is from 5 to 15 fold, this range varying somewhat with the character of the solvent and of the material to be treated.

It has also been found that the process of treating with inorganic acids in the presence of a solvent as described above with regard to petroleum ether-insoluble acids is also applicable without essential modification to the treatment of other acidic fractions arising in the oxidation of petroleum, e.g. the petroleum-soluble acids, the oil-insoluble phase and constituents thereof, or the oil-soluble phase in-toto, in which case the unreacted stock may form a portion or all of the diluent-solvent. It is obvious that in these diverse applications the diluent-solvent must be so chosen that it is capable of dissolving the material to be treated.

In general it is advantageous to use a solvent with a boiling range differing from that of the material treated, in order that such solvent as is subsequently dissolved or emulsified in the soap phase during the subsequent alkali extraction may later be removed by evaporation or distillation. This is not essential, however, in case small traces of the solvent are not objectionable, and furthermore the presence of the diluent tends to suppress the degree of such emulsification.

Where it is not deemed advantageous to separate the neutrals as a separate fraction, the solvent may be removed from the treated material by evaporation or distillation, in which case it is essential that the solvent be of a different boiling range from that of the material treated.

The acid numbers and saponification values presented herein refer to the milligrams of potassium hydroxide necessary to neutralize or saponify, respectively, one gram of the material in issue.

While the invention is set forth in detail specifically in the examples given hereinabove, it is to be understood that the process is compre-

hended in its broadest aspects, and that the various phases of said invention are to be limited only by the scope of the appended claims.

I claim:

5. 1. A process of treating products of liquid phase oxidation of naphthenic petroleum oils, which comprises separating the products of oxidation into a phase soluble in the unreacted oils and a phase insoluble therein, treating the oil-soluble phase to isolate therefrom an acidic fraction insoluble in petroleum ether, commingling said acidic fraction with petroleum ether thereby separating an acidic fraction insoluble in said petroleum ether, dissolving said petroleum ether insoluble acidic fraction in a solvent selected from the class consisting of benzene, toluene and mixtures thereof with naphtha and chloroform, and reacting said solution with an inorganic acid.
10. 2. A process for treating products of liquid phase oxidation of naphthenic petroleum oils which comprises separating said products of oxidation into a phase soluble in the unreacted oils and a phase insoluble therein, commingling said oil soluble phase with an aqueous alkali solution to saponify the carboxylic acids and the easily saponifiable lactones produced by the oxidation step, separating the aqueous soap solution from the unsaponified mixture, liberating the acids from said soap solution, separating the acidic fraction thus produced from the aqueous phase, extracting said acidic fraction with petroleum ether to reject an acidic fraction insoluble therein, and treating said petroleum ether insoluble acidic fraction with an inorganic acid selected from the class consisting of the oxygen-containing di- and tri-basic inorganic acids.
15. 3. In a process according to claim 2 wherein the acid treating step is followed by the removal of the acid sludge formed during said acid treating step thereby producing a refined petroleum ether insoluble acid fraction having excellent resin-forming characteristics.
20. 4. A process for treating products of liquid phase oxidation of naphthenic petroleum oils which comprises separating said products of oxidation into a phase soluble in the unreacted oils and a phase insoluble therein, commingling said oil soluble phase with aqueous alkali solution to saponify the carboxylic acids and the easily saponifiable lactones produced by the oxidation step, separating the aqueous soap solution from the unsaponified mixture, liberating the acids from said soap solution, separating the acidic fraction thus produced from the aqueous phase, extracting said acidic fraction with petroleum ether to reject an acidic fraction insoluble therein, commingling said petroleum ether insoluble acidic fraction with a solvent in which said fraction is soluble, and treating said solution with optimum quantities of sulfuric acid to form an acid sludge and a refined acid fraction having resin-forming characteristics.
25. 5. In a process according to claim 4, wherein the petroleum ether insoluble acids are dissolved in benzene and wherein the concentration of the sulfuric acid employed for the acid treatment ranges from about 40 to approximately 95%.
30. 6. In a process according to claim 4, wherein the petroleum ether insoluble acids are dissolved in benzene in a quantity of one part of the acids to approximately 9 parts of benzene and the solution thus produced is then reacted with sulfuric acid employed in quantities ranging from about 1 to 5 volume percent as calculated on the basis of the volume of the solution treated.

ARTHUR L. BLOUNT.
